UNITED STATES PATENT OFFICE.

WILLIAM JACOBY, OF SIOUX FALLS, SOUTH DAKOTA, ASSIGNOR TO AUTOMATIC TOOL SUPPLY CO., OF SIOUX FALLS, SOUTH DAKOTA, A CORPORATION OF SOUTH DAKOTA.

WRENCH.

1,243,300.

Specification of Letters Patent. Patented Oct. 16, 1917.

Application filed June 13, 1917. Serial No. 174,532.

To all whom it may concern:

Be it known that I, WILLIAM JACOBY, a citizen of the United States, residing at Sioux Falls, in the county of Minnehaha and 5 State of South Dakota, have invented certain new and useful Improvements in Wrenches; and I do hereby declare the following to be a full, clear, and exact description of the same, reference being had to the 10 accompanying drawings, forming part of this specification.

This invention relates to improvements in wrenches, more especially to that type of wrench known as the "ratchet wrench."

15 The general object of the invention is the provision of an exceedingly reliable and efficient ratchet wrench construction embodying movable jaws whereby the wrench may be quickly adjusted to accommodate 20 nuts of different sizes, and in which the jaws, when adjusted in position on a nut, will be effectively locked against displacement relatively to the nut.

With the above and other objects in view, 25 the invention consists in certain novel constructions, arrangements and combinations of parts hereinafter described in a preferred form and particularly pointed out in the claims at the end of the specification.

30 In the drawings,—

Figure 1 is a plan view of a wrench constructed in accordance with the present improvements.

Fig. 2 is a side longitudinal elevation of 35 the same.

Fig. 3 is a vertical longitudinal section on the line 3—3 of Fig. 1 showing the jaws in normal position.

Fig. 4 is a view similar to Fig. 3, but showing the jaws after they have been advanced toward each other in position for clamping a nut.

Fig. 5 is a transverse vertical section on the line 5—5 of Fig. 1.

45 Like characters of reference in the several figures indicate the same parts.

In the illustrated embodiment of the invention, the wrench handle is indicated by the reference character 1, said handle being 50 of any preferred construction and provided at one end with a head 2, preferably substantially circular in contour, as shown. The head 2 is formed with a central cylindrical bore 3, as shown more particularly in 55 Figs. 3, 4, and 5, having an upper portion 4

of relatively large diameter and a lower portion 5, of slightly reduced diameter whereby an inner annular flange 6 is formed within the head 2, for a purpose which will presently appear. The cylindrical bore 3 60 constitutes a bearing in which a jaw carrier 7 is rotatably mounted. Said jaw carrier includes in its construction a hollow cylindrical member 8, the outer wall of which is provided with an annular laterally-projecting flange 9 adapted to rest on the annular flange 6 of the wrench head, when the jaw carrier is inserted in the bore thereof from the top of the wrench, as viewed in Figs. 3, 4 and 5. The flanges 6 and 9 constitute a stop preventing axial displacement of the cylindrical jaw carrier in one direction, but without preventing free relative rotation of the jaw carrier and wrench head. For locking said carrier on the head against 75 axial displacement in the opposite direction, the cylindrical member thereof is threaded at its lower end which projects beyond the bottom face of the wrench head, as shown at 10, and screwed on said threaded portion 10 of the jaw carrier is a locking ring 11 adapted to abut against the bottom face of the wrench head.

The jaw carrier 7 is intended for the support of the jaws, and for this purpose the 85 interior of the cylindrical member 8 is provided with a pair of diametrically oppositely disposed segmental members 12 secured to the cylindrical member 8 in any preferred manner, with the arcuate faces of 90 the segmental members abutting against the inner cylindrical face of the member 8. Each segmental member is formed with a pair of spaced bearing sockets 13 extending from the plane face of the cylindrical member and located in line with the pair of similarly spaced sockets in the other member. Pivoted in each pair of oppositely disposed 95 alined sockets 13 is the lower end of a jaw shank 14, there being studs 15 respectively 100 projecting laterally from the opposite edges of each jaw shank, which studs enter the oppositely disposed sockets 13. The pair of shanks are thus mounted in such manner in the segmental bearings of the jaw carrier 105 that they may move toward and away from each other on axes transverse with respect to the axis of the carrier. For normally keeping the jaw shanks apart, springs 16 are secured within recesses 17 formed in the 110

plane faces of the segmental members. Each spring is provided at its opposite ends with projections 18, which respectively fit within recesses 19 formed in the opposite 5 jaw shanks.

Mounted on each jaw shank 14 above the jaw carrier is a jaw head or jaw proper 20 having a flat gripping or clamping face 21 disposed diametrically opposite to a similar face formed on the jaw 20 of the opposite shank. The jaws 20 are further provided with lateral extensions 22 projecting outwardly from their respective shanks, and to permit complete movement of the jaws away 10 from each other under the tension of the springs 16, the cylindrical member 8 of the jaw carrier 7 may be provided with diametrically opposite cut away portions 8^a through which pass the lateral extensions 22 15 of the jaws, see Fig. 3. The under horizontal face of the lateral extension of each jaw is downwardly curved or arcuate as shown at 23, and the curved faces of said extensions are engaged by suitable means hereinafter described for moving the jaws 20 toward each other to force the gripping faces of said heads into firm clamping engagement 25 with a nut to which the wrench is applied.

30 Journaled on the cylindrical member of the jaw carrier is a jaw shifting ring 24 located above the upper face of the wrench head 2 and rotatable on an axis substantially coincident with the axis of rotation of the 35 jaw carrier and in a plane fixed with respect to the wrench head. The outer cylindrical face of said ring is formed with teeth 25 and the upper end face of the same is formed to constitute a cam face having 40 diametrically opposite, inclined raised portions 26 connected by depressed portions 27. The altitudes of the respective raised portions are, it will be noted, substantially parallel with the axis of rotation of both 45 the jaw carrier and jaw shifting ring. Said cam face engages the curved faces of the lateral extensions of the respective jaws, and on movement of the ring relatively to the jaw carrier to bring the inclined raised 50 portions 26 of the cam face into juxtaposition with the lateral extensions of the jaws, the latter are forced or shifted toward each other, thereby advancing the gripping faces so as to cause them to grip a nut positioned 55 between them. On further movement of the ring 25 to bring the depressed portions 27 of the cam face into juxtaposition with the lateral extensions of the jaws, the latter are 60 permitted to move apart under the tension of the springs 16 interposed between the jaw shanks whereby the jaws are released from gripping engagement with a nut and the wrench may be quickly detached from the nut.

65 Mounted on the wrench handle and co-

operable with the toothed portion of the jaw-shifting ring, is a reversible detent mechanism consisting preferably of the following instrumentalities:—A pawl 28 pivoted on the handle is provided with a head 70 having two prongs or fingers 29, separated some little distance from each other, as shown in Fig. 1. Pivotal movement of the pawl in one direction, will bring one finger of the pawl into engagement with the toothed 75 portion of the ring on one side of the latter and concurrently move the other finger which is located on the other side of the jaw-shifting ring, out of engagement with the toothed portion of the latter. Accordingly, by an adjustment of the pawl 28, the 80 jaw-shifting ring may be locked against rotation relatively to the wrench head 2 in either direction. When so locked against such relative rotation, however, the pawl permits 85 rotation of the jaw-shifting ring in reverse direction. For shifting the pawl, there is provided a pivoted lug 30 having a curved face 31 adapted to enter a pocket formed by the curved end 32 of the pawl opposite to the 90 pronged end thereof. Said pivoted lug 30 is provided with a plunger 33 extending into a socket formed in the lug and pressed outwardly from the curved face of the lug into engagement with the curved end 32 of the 95 pawl by means of a spring 34 located in the socket behind the inner end of the plunger. The spring permits the pawl and plunger to yield when the jaw-shifting ring is rotated reversely to the direction in which the 100 latter is locked against rotation relatively to the wrench head.

The operation of the above described ratchet wrench is as follows:—Assuming that a nut provided with a right hand thread 105 is to be applied to a bolt, the pawl 28 is adjusted by shifting the lug 30 so as to prevent relative rotation of the jaw-shifting ring and wrench head and handle, toward the right (i. e., toward the left in Fig. 1 as the wrench 110 is shown upside down). The wrench is then applied to the nut, which may be effected by first adjusting the jaw-shifting ring 25 so that the depressed portions 27 of its cam face are in juxtaposition with the lateral extensions of the jaws, permitting the jaws to 115 spring apart and be passed over the nut. The wrench is then moved toward the right. As the jaw-shifting ring 25 is locked against rotation toward the right relatively to the 120 wrench head, said ring and wrench move relatively to the jaw carrier 7, bringing the raised portions 26 of the cam face into engagement with the lateral extensions of the 125 jaws, and thereby forcing the latter into firm gripping engagement with the nut. When such gripping engagement takes place, the jaws cannot move farther inwardly and hence no further relative movement can take place between the jaw carrier and the jaw- 130

shifting ring. All the parts are consequently locked together, and the wrench may then be operated back and forth in the manner of an ordinary ratchet wrench to tighten 5 up the nut. When it is desired to remove the wrench from the nut, the ring 25 may be locked against rotation toward the left relatively to the wrench head and the ring and head rotated in that direction, where- 10 upon the relative rotation of the ring and jaw carrier will cause the depressed portions 27 of the cam face to move again into juxtaposition with the lateral extensions of the jaws, permitting the latter to free them- 15 selves from the nut. Or the ring may be shifted manually by first adjusting the pawl to neutral position, wherein neither of the prongs 29 are in engagement with the teeth of the ring. When the pawl is in neutral 20 position, the ring may be rotated freely relatively to the wrench head and jaw carrier.

In applying a nut provided with a left hand thread or unscrewing a nut with a right hand thread, the operation is just the 25 reverse as that heretofore described.

What is claimed is:

1. A wrench comprising, in combination, a handle formed with a head, a jaw carrier rotatably mounted in the head, jaws mounted 30 on said jaw carrier and movable toward and from each other, elastic means acting to urge said jaws apart, a jaw-shifting ring rotatably mounted on the jaw carrier, and provided with a cam surface engageable with 35 said jaws to move them toward each other on relative rotation of the jaw carrier and ring, and means for locking said jaw-shifting ring against rotation relatively to the head in one direction while permitting such 40 relative rotation in the opposite direction.

2. A wrench comprising, in combination, a handle formed with a head, a jaw carrier rotatably mounted in the head, jaws mounted 45 on said jaw carrier and movable toward and from each other, elastic means acting to urge said jaws apart, a toothed jaw-shifting ring rotatably mounted on the jaw carrier and provided with a cam surface engage-

able with said jaws to move them toward each other on relative rotation of the jaw 50 carrier and ring, and reversible detent mechanism adapted to engage a tooth of the jaw shifting ring for locking the same against rotation relatively to the head in one direction while permitting such rotation in the 55 opposite direction, substantially as described.

3. A wrench comprising, in combination, a handle formed with a head, a jaw carrier rotatably mounted in the head, jaws mounted 60 on the jaw carrier, each jaw being movable toward and away from the other jaw on an axis transverse to the axis of rotation of the jaw carrier, a jaw-shifting ring journaled on the jaw carrier and rotatable in a plane fixed with relation to the head on an 65 axis substantially coincident with the axis of the jaw carrier, said jaw-shifting ring being formed with opposite inclined faces engageable with the jaws, whereupon rotation of the ring on its axis moves the jaws 70 toward each other, and means for locking said ring against rotation relatively to the head in one direction while permitting such relative rotation in the opposite direction.

4. A wrench comprising, in combination, 75 a handle formed with a head, a jaw carrier rotatably mounted in the head, jaws mounted on the jaw carrier, each jaw being movable toward and away from the other jaw on an axis transverse to the axis of rotation 80 of the jaw carrier, a jaw-shifting ring journaled on the jaw carrier and rotatable in a plane fixed with relation to the head on an axis substantially coincident with the axis of the jaw carrier, the end face of said ring 85 being formed with opposite inclined portions and the jaws being provided with lateral extensions engageable by said opposite inclined portions, whereupon rotation of said ring on its axis is effective to move the jaws 90 toward each other, and means for locking said ring against rotation relatively to the head in one direction, while permitting such relative rotation in the opposite direction.

WILLIAM JACOBY.
